Boston Type Foundry, No. 104 Milk Street, Boston.

UNITED STATES PATENT OFFICE.

JOHN K. ROGERS, OF BROOKLINE, MASSACHUSETTS.

DESIGN FOR A FONT OF PRINTING-TYPE.

SPECIFICATION forming part of Design No. 12,120, dated January 11, 1881.

Application filed September 23, 1880. Term of patent 3½ years.

To all whom it may concern:

Be it known that I, JOHN K. ROGERS, of the town of Brookline, in the State of Massachusetts, have invented and produced a new and original Design for a Font of Printing-Types, of which the following is a specification, the nature of the design being clearly shown in the accompanying typographical impressions, to which reference is made.

10 My design consists of a font of capital letters, figures, points, right and left end pieces, center-piece, and logotype "and," as shown.

The general character of the style is a Gothic or sans-seriph letter, with novel characteristics,

which may be indicated as follows: First, the 15 internal lines, which are usually horizontal, are in this font sloped from right to left, as in the A, B, E, F, H, P, and R; second, novel curved lines are introduced in C, G, K, M, N, S, U, V, W, X, and Y. These characteristics constitute a new and original design.

What I claim is—

The design for a font of printing-types here-
in shown and described.

JOHN K. ROGERS.

Witnesses:

THOS. H. WAKEFIELD,
JOHN L. WAKEFIELD.
